UNITED STATES PATENT OFFICE.

HARRY MARVIN SPENCER, OF DUNMORE, PENNSYLVANIA.

SPARK-PLUG

1,068,462.

Specification of Letters Patent

Patented July 29, 1913

Application filed February 27, 1912. Serial No. 680,210

To all whom it may concern:

Be it known that I, HARRY M. SPENCER, a citizen of the United States, residing at Dunmore, in the county of Lackawanna and State of Pennsylvania, have invented a new and useful Spark-Plug, of which the following is a specification.

The present invention relates to improvements in spark plugs, the primary object of

- 10 the invention being the provision of a novel construction and arrangement of sparking terminals of a spark plug used in connection with the jump-spark system generally employed in connection with the ignition
15 of explosive motors, the stem carrying the positive sparking element being disposed for rotation and provided with a plurality of sparking terminals disposed below the
20 sparking terminals of the negative element, so that the rotation of the stem carrying the positive element will automatically clean the contact points of both elements without the necessity of the removal of the plug from the explosive motor.
25 A further object of the present invention is the provision of a novel form of spark plug which is readily applied to the usual spark plug receiving receptacles of explosive motors, the negative element of which is
30 projected within the explosive or ignition chamber of such motor and is provided with a plurality of downwardly projecting spark terminals, while disposed concentrically of the same is a stem carrying the positive
35 sparking terminals, one to each negative sparking terminal, and so disposed that the greatest possible sparking surface may be provided, so that a working spark plug will be produced, even though a majority of such
40 terminals should be carbonized, the said stem carrying the positive sparking element being so disposed that the same may be rotated without the removal of the plug from the motor, such rotation rotating the positive
45 sparking element so as to clean the carbon adhering to the negative and positive terminals.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a vertical central sectional view of the complete spark plug in the position it assumes when in operable relation within an explosive engine cylinder. Fig. 2 is a side elevation of the complete spark plug removed. Fig. 3 is a bottom plan view of the spark plug. Fig. 4 is a perspective view of the positive sparking terminals. 60 65

Referring to the drawings, the numeral 1 designates the body of the explosive motor which is provided with the usual spark plug receiving and threaded aperture 2, for the reception of the hollow cylindrical body 3, which carries the hexagonal metallic nut 4 of the-sparking plug, this connection forming a ground through the motor.

Mounted concentrically within the nut 4 is a porcelain sleeve 5, the same extending the full length of the cylindrical body 3 and above the same to form the proper insulation for the plug. Fitted upon the threaded portion of the body 3 and holding said body 3 and sleeve 5 relatively together, is a cup-shaped lock nut 6. The positive sparking terminal carrying stem or rod 7 is mounted concentrically of the sleeve 5 and has its lower end disposed below the sleeve 5, whose lower face also terminates slightly below the face of the lower end of the negative sparking terminal carrying sleeve 3.

Mounted upon the upper end of the porcelain sleeve 5 and surrounding the adjacent portion of the stem 7 but out of contact therewith, is a metal cap or disk 8, which is held relatively to the sleeve against rotation therefrom by means of a screw 9. This disk or cap 8 is provided with the concentric receptacle 10 for the reception of a coiled spring 11, which rests upon the upper end of the porcelain sleeve 5 and bears upon the under side of the metal disk 12, which is held relatively upon the stem 7 and rotatable therewith by means of the set screw 13. The disks 8 and 12 are provided with the indicating marks 14 and 15 respectively, which as shown in Fig. 1 indicate that the sparking terminals of the plug are in proper position for producing the maximum spark, the stem 7 being so mounted that the same may be rotated to the right or left, as viewed in Fig. 1, to throw the said marks 14 and 15 out of alinement and indicate to the operator the positioning of the sparking terminals, as will later appear.

Adjustably mounted upon the stem 7 above the disk 12, is a locking milled disk 16

6

which with the disk 12 provides a means for clamping the terminal plates 17 of the positive conductor therebetween so that the current is properly conducted to the stem 7 and the sparking terminals thereof.

In order to rotate the stem without the necessity of removing the spark plugs from the motor cylinder, the milled disk 18 provided with the shouldered portion 19 is fitted upon the extreme upper end of the stem 7 above the milled disk 16, the pin 20 being so disposed as to rigidly secure the same in position so that the stem 7 may be rotated either by the oscillation through the milled disk 18 or by means of a wrench placed upon the shouldered projection 19.

20 Formed integral with and projecting from the lower end of the cylinder 3, said cylinder 3 forming the negative element of the spark plug, are the negative sparking terminals 21, each one of which is disposed at a quadrant about the circumference, as illustrated in Fig. 3 and is provided with the lower inclined or beveled portion *b*,
25 while keyed upon and carried by the lower end of the stem 7, is a disk 22 of a lesser diameter than the lower end of the porcelain sleeve 5, said disk being held upwardly and in engagement with the lower end of
30 the said sleeve by means of the spring 11, and carrying the radially disposed positive sparking terminals 23, each one of which is disposed to coact with the negative sparking terminals 21 and is provided with the
35 upper inclined beveled portion *b* which coacts with the beveled portion *a* of the terminals 21, so that the rotation of the stem 7 in the direction of the arrow Fig. 3, will cause the sparking terminals 23 to ride
40 upon the beveled portion of the sparking terminals 21, such riding due to the spring 11, producing sufficient friction to cut the carbon from the terminals 21 and thus permitting the terminals 23 to be snapped over
45 the terminals 21 to assume any of the positions that will produce the maximum spark, or as shown in dotted lines Fig. 3. It will thus be seen that the terminals 23 are rotated without the necessity of the removal
50 of the plug from the motor and that all of the terminals may be properly positioned by means of the indicating marks 14 and 15, the relative location of the same indicating visually the positioning of the positive terminals
55 relatively to the negative terminals. The adjacent spark gap forming faces of the pairs of terminals 21—23, are inclined and when in proper sparking relation are separated, the lower end of the insulating
60 body 5, holding the terminals 23, by means of its engagement with the disk 22, out of contact with the terminals 21 and also the lower end of the bushing 3. Thus when the

disk 22 is rotated, the inclined surfaces a ride upon each other and the accumulated carbon is scraped from both surfaces, so that the terminals are cleaned without the removal of the plug from the engine cylinder. 65

What is claimed is:

1. A spark plug, having a cylindrical metallic body, a plurality of downwardly projecting sparking terminals carried upon the lower end of said cylindrical body, an insulating body of greater length than the metallic body mounted concentrically of and within the metallic body and having its lower end disposed to project slightly below the lower facial plane of the lower end of the metallic body, a rod mounted rotatably and concentrically of the insulating body, the upper end thereof projecting beyond the upper end of the insulating body, a sparking terminal carrying member disposed upon the lower end of said rod below the cylindrical and insulating bodies, the same being provided with a similar number of sparking terminals to that of the metallic body, the sparking terminals of both elements being of such a size as when disposed in radial alinement to contact, whereby the rotation of the rod will clean the sparking terminals of both elements, and a spring mounted upon the upper end of the rod and insulating body to hold the sparking terminal carrying member of the rod resiliently against the under side of the insulating body. 75 80 85 90 95

2. A spark plug, including a metal bushing having a plurality of sparking terminals with lower inclined faces projecting from its lower end, a sleeve of insulation disposed within the bushing and having its lower end projecting slightly below the lower end of the bushing but within the facial plane of the terminals, a stem mounted for sliding and rotary movement within the sleeve, a plurality of radial sparking terminals, one to each terminal of the bushing, mounted upon the lower end of the stem and limited against inward movement by the lower end of the insulating sleeve, each radial terminal being provided with an inclined face for scraping action to clean the terminals of the bushing and for adjustment therewith to produce a spark gap between the terminals, and a spring for holding the stem and radial terminals in such position.

In testimony that I claim the foregoing 120
as my own, I have hereto affixed my signature
in the presence of two witnesses.

HARRY MARVIN SPENCER.
